ELECTRIC IRON

Albertine Ruelland, New York, N. Y.

Application March 31, 1931, Serial No. 526,614

6 Claims. (Cl. 219—25)

This invention relates to improvements in electric irons and, more particularly, to improvements in electric irons of the type shown and described in my prior patents No. 1,563,591 and No. 5 1,708,957.

The type of iron described in the patents referred to comprises a body portion containing a heating element and an elbow handle pivotally connected to the body portion and having a free end. Electric cords are connected with the heating element terminals and lead thru the elbow handle to its free end where they enter a socket. The socket is adapted to receive the plug of a second cord which, in turn, is connected 10 with a source of current.

Disadvantages have been associated with this construction. The arrangement of the electrical connections in the elbow handle renders them inaccessible for repair or replacement, while the 20 passage of the electrical connections from the free end of the handle to the source of current is inconvenient.

The present invention provides means whereby the above disadvantages are overcome.

One of the objects of my invention is to provide in an electric iron having a body containing a heating element and having a handle with a free end, a member for pivotally connecting the other end of the handle to the iron, said member having an opening adapted to receive the plug of an electrical conductor, whereby the iron may be connected with or disconnected from a source of current.

Another object is to provide an electric iron as above in which the connecting member is provided with a hollow portion adapted to receive a boss on the iron for pivotally connecting the body of the iron and the handle; the connecting member having an internal flange providing an opening which is adapted to receive and closely fit the plug of an electrical conductor.

Another object is to provide an electric iron comprising a body portion, a handle having a free end, and a connecting member for pivotally connecting the handle to the body of the iron, the connecting member having an opening adapted to receive and closely fit the plug of an electrical conductor, and to provide a handle having an inclined free end, the end being inclined 50 outwardly and downwardly.

With the above and other objects in view, my invention consists in the parts, improvements and combinations more fully pointed out hereinafter.

Referring now to the drawing:

Figure 1 is a side elevation of the iron and

stand, showing the connecting member between the iron body and handle adapted to receive an electric plug; and also showing, in dotted lines, the relative position of the iron and stand when the iron is to be shipped or stowed away.

Figure 2 is a perspective view of the iron in one of the positions in which it can be placed for use.

Figure 3 is a horizontal section taken on the line 3—3 of Figure 1, showing the connecting member and its internal flange, providing an opening adapted to receive and closely fit the plug of an electrical conductor.

Figure 4 is a detail view taken on line 4—4 of Figure 1 and shows the adjustable connections between the connecting member and the boss of 15 the iron.

Figure 5 is a cross-sectional view of a square-shaped handle for the iron, and

Figure 6 is a cross-sectional view of another form of handle, the handle being round and 20 provided with a longitudinal notch.

In the drawing the electric iron comprises a body having a soleplate 1, a cover plate 2, and a boss 3 mounted on the plate 2. Within the body of the iron is a heating element 4 connected by 25 wires 5, with the terminals of a socket 6, carried by the boss.

The handle 7, of the iron normally projects from the iron in a plane parallel to the plane of the body of the iron, see Figure 1. One end of 30 the handle 7 is free and the other end is connected to the body of the iron.

In the form shown a connecting member or sleeve, 8 is provided for connecting the handle to the body of the iron. This member has a vertical portion which may be suitably connected to one end of the handle 7. The lower portion of member 8, is circular and hollow and is adapted to receive the boss 3 of the iron. This provides a pivotal connection between the handle and the 40 body of the iron.

Means are provided for securing the iron and handle together in adjusted position. As shown, the lower circular portion of connecting member 8 is provided at 9 with a slot which extends half-way around the connecting member. Each end of the slot terminates in a circular opening or notch 10, adapted to receive a housing generally designated 11 which carries a set screw 12. A coil spring 13, is carried by the housing and surrounds the set screw. One end of spring 13 is adapted to engage the head of the set screw, while the other end of the spring engages shoulders 14, provided by the housing. The set screw is adapted to pass thru the inner end wall of the hous- 50

ing to interconnect and engage the boss 3 of the iron to hold the handle and iron in adjusted position. By these means the handle and iron may be secured together in the positions shown in Figure 2, or in full lines in Figure 1; or the set screw 12 may be loosened and the handle swung 180 degrees into the position shown in dotted lines in Figure 1, and the set screw then used to secure the handle and iron together.

10 Heretofore the electrical connections comprised an electric cord which passed from the terminals of the heating element of the iron, thru the handle to a socket at the free end of the handle. This socket was adapted to receive the plug 15 of a second electric cord which, in turn, was connected to a source of current.

With this arrangement the electrical connections were inconveniently arranged and were often in the way of the user, while the portion 20 of the connections which passed thru the handle was inaccessible for repair or replacement.

In accordance with the present invention the connections are so arranged as to be out of the way of the user and as to be accessible for repair 25 or replacement. The connections do not pass thru the handle of the iron, but pass thru the connecting member between the body of iron and the handle. As shown, the connecting member 8 is provided with an internal flange 15, see Figure 3, which provides an opening adapted to receive and closely fit the plug 16 of a cord 17, which is adapted to be connected with a source of current (not shown). The opening provided by flange 15, is adapted to receive a plug of standard size and construction. The use of special plugs is thus dispensed with and the cost of manufacture of the iron is reduced.

The iron is preferably used in conjunction with the stand shown herein, and more particularly 40 described and claimed in my prior Patent 1,708,597. The stand comprises a pair of spaced plates 18 and 19. Plate 18 is provided with a slot at 20, while plate 19 is provided with slots at 21, 22. The stand is supported on feet 23, and stop plates 45 24 are provided at the sides for positioning the iron on the stand. In the preferred form the feet and stop plates are composed of a single piece of metal.

The stand contributes to the utility of the iron. 50 It provides means whereby the iron may be supported in a number of various ironing positions so that the iron may be used for different classes of work. It may, for example, support the iron in an upstanding position as shown in Figure 2. 55 Or it may be used to enclose the body of the iron when the iron is not in use or is being shipped, as shown in dotted lines in Figure 1.

The present invention enables the use of the iron and stand to be improved. Heretofore, when 60 the iron was supported in the stand in upstanding position, such as shown in Figure 2, the handle of the iron did not rest on the support. The plug of the electrical connections which passed thru the handle rested on the support. With this 65 arrangement there was a tendency for the iron to wobble as it was being used. By providing means whereby the electrical connections do not pass from the free end of the handle, this end 70 of the handle rests on the support, and thus firmly supports the iron in the stand and avoids the tendency to wobble.

In the preferred form the free end of the handle is inclined outwardly and downwardly to 75 prove the support afforded by the free end of the

handle when in position such as shown in Figure 2.

Other forms of handle may, of course, be provided. If desired the handle 25, see Figure 5, of square cross-section, may be used. Or a round 5 handle 26, Figure 6, may be used and provided with a longitudinal notch 27. When the form of handle shown in Figure 6, is used, one of the plates of the stand is provided with a projecting lip (not shown) which is adapted to be received 10 in the notch 27, and prevent turning of the iron when in ironing position on the stand.

Having thus described the invention, its operation will be clear. It will be understood that changes may be made in carrying the invention 15 into effect, without departing from the principle thereof.

What I claim is:

1. An electric iron comprising a body portion having a heating element, a boss on the body portion, an electrical socket in the boss and connections between the socket and heating element, a handle having a free end, a connecting member connected to the other end of the handle and having a hollow portion adapted to receive said boss for pivotally connecting the handle to the iron, said member being adapted to receive the plug of an electrical conductor, said member being provided with a horizontal slot, and a set screw adapted to pass thru overhanging means 30 having a portion passing through said slot and connected to said boss, and means surrounding said overhanging means for adjustably holding said connecting member relative to said boss.

2. An electric iron comprising a body portion, 35 having a heating element, a boss on the body portion and having a socket, spaced terminals within said socket, connections between the terminals and heating element, a handle having a free end, a connecting member connected to the other end of the handle and adapted to receive the boss for pivotally connecting the handle to the iron, said connecting member having an internal flange providing an opening adapted to receive and closely fit a substantially flat plug of 40 45 an electrical conductor.

3. An electric iron comprising a body portion having a concealed heating element, a boss extending upwardly from said body portion and including a plug receiving socket, spaced plug 50 engaging terminals disposed within said socket and electrically associated with said element, a free laterally extending handle having a depending tubular sleeve surrounding said boss and rotatable relative thereto, said sleeve having an ar- 55 cuate slot, an adjustable member guided within said slot and having a terminal portion carried by said boss, a housing surrounding said member and resilient means confined within said housing and acting against said member, said housing 60 having a portion coacting with said boss to prevent displacement of said sleeve relative thereto.

4. An electric iron comprising a body portion having a concealed heating element, a boss extending upwardly from said body portion and including a plug receiving socket, spaced plug 65 engaging terminals disposed within said socket and electrically associated with said element, a laterally extending handle having a depending tu- 70 bular sleeve surrounding said boss and rotatable relative thereto, said sleeve having an arcuate slot, a member adjustable relative to said boss and carried thereby, said member extending through said slot and overhanging the latter, a 75

- housing surrounding said member and a spring interposed between one end of said housing and an opposing end of said member for urging said housing against said boss to prevent movement of said sleeve relative to said boss.
5. An electric iron comprising a body portion having a concealed heating element, a boss extending upwardly from said body portion and including a plug receiving socket, spaced plug 10 engaging terminals disposed within said socket and electrically associated with said element, a laterally extending handle having a depending tubular sleeve surrounding said boss and rotatable relative thereto, said sleeve having an arcuate slot having relatively enlarged terminal notches, clamping means to prevent or permit movement of said sleeve relative to said boss
- carried by said boss and guided by said slot and removably receivable in said notches.
6. An electric iron comprising a body portion having a concealed heating element, a boss extending upwardly from said body portion and including a plug receiving socket, spaced plug 15 engaging upstanding terminals disposed within said socket and electrically associated with said element, a free laterally extending handle having a depending tubular sleeve surrounding said boss 10 and rotatable relative thereto, said sleeve having an arcuate slot having relatively enlarged terminal notches, and means for adjustably holding said sleeve relative to said boss comprising manipulatable clamping means carried by said boss 15 and guided by said slot and removably and selectively receivable in said notches.

ALBERTINE RUELLAND.
